BY MESNE ASSIGNMENTS, TO C-O-TWO FIRE EQUIPMENT COMPANY, OF LOS
ANGELES, CALIFORNIA, A CORPORATION OF CALIFORNIA

GAS-PRESSURE MEANS FOR RELEASING CONNECTIONS

Application filed May 20, 1929. Serial No. 364,523.

Our invention relates to apparatus used in extinguishing fires and particularly to the apparatus used in extinguishing fires in enclosures such as a compartment or room.

5 When a fire extinguishing fluid or gas is introduced into a room for the purpose of extinguishing a fire therein, it is very desirable to have all the external openings to the room closed, so as to prevent the escape 10 of the extinguishing gas or fluid from the room and also to prevent the flames of the fire from escaping and spreading outside the room. In practice it is desirable that the closing of the openings to the room occur 15 automatically with the release of the extinguishing fluid in order that the one operation of releasing the fluid releases the fluid and closes the openings.

It is an object of our invention to provide 20 an apparatus which will automatically release a connection, thereby allowing the closing device to close the opening to the room when the extinguishing fluid is admitted thereto, and which will be operated by a jet 25 of the fluid striking an operating member of the device.

It is also desirable from the standpoint 30 of efficiency in admitting the extinguishing fluid to the room in the minimum amount of time, to have an operating member which will be operated by the escaping fluid and which, after operation, will not interfere with the escape of the fluid.

In our invention we have made it an object 35 to have the operating means operable by the escaping fluid, but after operation, to have the operating means detached from the remainder of the device so as not to interfere with the escape of the extinguishing fluid.

40 It is very essential in devices of this class that the operation be absolutely certain so as to prevent the possibility of the fire not being extinguished due to failure of the apparatus.

45 It is another object of our invention to provide a device which will be positive in operation.

We also have as an object of our invention the production of a device which will 50 be simple in its construction and operation,

as these factors contribute to the positiveness of its operation and the lowering of its manufacturing cost.

In the accompanying drawings we have shown a preferred form of our invention. 55

Fig. 1 is a view taken on the interior of an enclosure showing the utility of our device.

Fig. 2 is a side view of the device showing it attached to a wall.

Fig. 3 is a view showing the appearance 60 of the operating member.

Fig. 4 is a sectional view taken on the line 4—4 of Fig. 2.

Fig. 5 is a sectional view taken on the line 5—5 of Fig. 4. 65

Referring to Figs. 2 to 5 inclusive in which the preferred form is shown, our device consists of a cylindrical body 11 which forms the framework of the device. To one side of the body 11 are attached feet 12 which support it on a wall 13 or similar support. An axial opening 14 is formed by walls of the body 11, into the upper end of which a nozzle 16 having an opening 17 is threaded 70 attached, and at the lower end of which a pipe nipple 18 is threaded attached. The nipple 18 is connected to a supply pipe 19 by a union 20.

The upper portion of the body 11 has a projection 21, which is provided with a threaded opening 22 into which a holding member in the form of a pin 23 is screwed. The pin 23 projects above an upper face 24 of the body 11 and has a rounding upper surface. 80

The operating member consists of a flat plate 26 having a solid portion 27 at one end. Midway between the portion 27 and the opposite tapered end 28 is an elongated opening 29 of proper size to receive the pin 23. A key 32 is placed in an opening 30 formed in the tapered end 28 and serves to attach a yoke 31 to the end 28 of the plate 26. The yoke 31 forms a convenient means for attaching a restraining member, such as a cord or rope, to the plate 26. 90

The operating member or plate 26 is detachable from the remainder of the device, in which condition it appears in Fig. 3. When attached to the remainder of the device it is 100

positioned so that a face of the portion 27 contacts the upper face 24 of the body 11, the pin 23 is inserted in the elongated opening 29 and the face of the portion 27 covers the nozzle opening 17. When in this position the plate 26 is held from moving lengthwise by the engagement of the pin 23 with the walls of the opening 29. When the portion 27 is raised vertically, as is done when a jet of fluid issuing from the nozzle 16 strikes the portion 27 of the plate 26, the walls of the opening 29 slide over the rounded portion of the pin 23 and the plate 26 is released. The pin 23 and the walls of the opening 29 form a releasable connection to restrain the plate 26 against lengthwise movement, the pin 23 and the walls of the opening being the holding members, and as such will be referred to in the appended claims.

In Fig. 1 we have shown an application of our invention. It should be understood that this is only an example and that our device is not confined to this use alone. In the illustration shown, the numeral 34 represents the device of our invention attached to the inside wall of an enclosure, such as a room having an opening in the form of a doorway 35. The doorway is closed by a closing member such as a door 36, which is supported on hangers 37 rolling on an inclined track 38. When the door 36 is not restrained, it normally moves down the track 38 on the hangers 37 and closes the doorway 35 in a well-known manner. A restraining member in the form of a cord or rope 39 is attached at one end to the door 36 and at the other end to the yoke 31 of the device 34.

In the normal position of the apparatus, the plate 26 is attached to the body 11, as explained before. This holds the plate 26 and likewise the rope 39, which is attached thereto, from horizontal movement. The rope 39 in turn holds the door 36 in open position.

In case of a fire in the room, the fire extinguishing fluid is released through the supply pipe 19, the nipple 18, the opening 14 in the body 11 and issues as a jet from the opening 17 in the nozzle 16. The jet of fluid issuing from the nozzle 16 strikes the flat portion 27 of the operating member 26 and causes it to move upward. This breaks the connection between the walls of the opening 29 and the pin 23, releasing the restraining member 39, which allows the door 36 to close the doorway 35. The operating member 26 being released from the device 34 is carried away from the device 34 by the closing of the door 36 and does not interfere with the escape of the fluid from the nozzle 16. Furthermore, the plate 26 is certain to be released from the device 34 because the pressure of the fluid moves the plate 26 at least a small distance from the face 24 of the body 11, and the top of the pin 23 is rounded so that in case the plate 26 is raised a small distance

from the face 24 the walls of the opening 29 are raised from their engagement with the pin 23, thus releasing the plate 26 from the device 34.

We claim as our invention:

1. In a fluid pressure operating device, the combination of: a body having a fluid opening formed therein; a releasable member to be moved by a jet of fluid issuing from said fluid opening; a primary holding member on said body; and a secondary holding member on said member adapted to engage said primary holding member to form a releasable connection therewith, said connection being releasable by the movement of said member.

2. In a fluid pressure operating device, the combination of: a body having a nozzle attached thereto; a releasable member to be moved by a jet of fluid issuing from said nozzle; a primary holding member on said body; and a secondary holding member on said operating member adapted to engage said primary holding member to form a releasable connection therewith, said connection being releasable by the movement of said operating member.

3. In a fluid pressure operating device, the combination of: a body having a fluid opening formed therein; a releasable member to be moved by a jet of fluid issuing from said fluid opening; a pin attached to said body; and walls forming an opening in said member and adapted to engage said pin so as to form a releasable connection therewith, said connection being releasable by the movement of said operating member.

4. In a fluid pressure operating device, the combination of: a body having a fluid opening formed therein; a releasable member adapted to close an outlet to said fluid opening and being adapted to be moved by a jet of fluid issuing therefrom; a primary holding member on said body; and a secondary holding member on said releasable member adapted to engage said primary holding member to form a releasable connection therewith, said connection being releasable by the operation of said releasable member.

5. In a fluid pressure operating device, the combination of: a body having a fluid opening formed therein; a releasable member adapted to close an outlet to said fluid opening and being operable by a jet of fluid issuing therefrom; a pin attached to said body; and walls forming an opening in said releasable member and adapted to engage said pin so as to form a releasable connection therewith, said connection being releasable by the operation of said releasable member.

6. In a fluid pressure operating device, the combination of: a body having a nozzle attached thereto; a releasable member adapted to close an opening in said nozzle and adapted to be moved by a jet of fluid issuing therefrom; a pin attached to said body; and walls

forming an opening in said releasable member and adapted to engage said pin so as to form a releasable connection therewith, said connection being releasable by the operation of said releasable member.

5 7. In a fluid pressure actuated device, a body, means whereby fluid under pressure may be discharged from the body, a releasable member, and means connecting the said member with the body whereby said member will be released upon the discharge of fluid from the body.

10 8. In a device of the character described, two elements, one a body having an opening for discharging fluid, the other a releasable member, and a releasable connection between the elements releasable upon the releasable member being moved by fluid discharging from the opening in the body.

15 9. In a device of the character described, two elements, one a body, having an opening for discharging fluid, the other a releasable member, and a releasable connection between the elements releasable upon movement of the releasable member by fluid discharging from the opening in the body, the said connection including a pin on one element engaging the other element.

20 In testimony whereof, we have hereunto set our hands at Los Angeles, California, this 14th day of May, 1929.

SCOTT E. ALLEN.
